John C. Clime

United States Patent Office.

JOHN C. CLIME, OF PHILADELPHIA, PENNSYLVANIA, ASSIGNOR TO HIMSELF AND J. MOORE HENDRICKS, OF SAME PLACE.

Letters Patent No. 75,527, dated March 17, 1868.

IMPROVED BEDSTEAD.

The Schedule referred to in these Letters Patent and making part of the same.

TO ALL WHOM IT MAY CONCERN:

Be it known that I, JOHN C. CLIME, of Philadelphia, Pennsylvania, have invented certain new and useful Improvements in Bedsteads; and I do hereby declare that the following is a full and exact description of the same, reference being had to the annexed drawings forming part hereof, and to the letters of reference marked thereon, in which drawings—

Figure 1 is a perspective view of bedsteads with my improvements applied thereto.

Figure 2 is a longitudinal vertical section of the same on the line *x y* of fig. 1.

My invention consists first, of a certain arrangement and combination of slats, coil springs, a middle supporting-bar, and an adjustable supporting-bar, placed at the head of the bedstead; second, in the employment of a hollow perforated tube, to contain camphor or other disinfecting-agent.

In the drawings, the parts marked A are stiff wooden slats, with notches, *a*, formed in the body of each slat at the two ends thereof. B are springs, formed as shown. The projecting arms or levers *b b* of the springs form loops, which take hold of the notches *a* in the slats. The springs B are applied at the head and foot of each of the slats A, and also at about the middle of the length of the slats; that is, in a full-sized bed, at about two feet six inches from the head-rail. C is a bar, to support the middle springs, which are so arranged that their projecting arms extend in opposite directions, as shown in fig. 2. The springs at the head of the bedstead are attached to movable bar D, which, being acted upon by thumb-screws, tighten or relax the springs. F is a perforated hollow tube, inserted through the coils of the springs B. This tube is intended to contain camphor, or any other disinfecting-agent, the odor of which escapes through the perforations *d*, shown in fig. 1.

Having thus described my invention, I do not claim the adjustable bars D, slats A, springs B, or middle supporting-bar C, separately, but I do claim, and desire to secure by Letters Patent—

1. The arrangement of the notched slats A, coil springs B, middle supporting-bar C, and adjustable head-bars D, when these several parts are constructed substantially as shown and described, for the purpose specified.

2. I claim the perforated hollow tube F in combination with the coil springs B, substantially as set forth.

JOHN C. CLIME.
